UNITED STATES PATENT OFFICE.

WILLIAM D. PATTON, OF PHILADELPHIA, PENNSYLVANIA, ASSIGNOR TO WILLIAM H. HORN & BROTHER INCORPORATED, OF PHILADELPHIA, PENNSYLVANIA, A CORPORATION OF PENNSYLVANIA.

TRUSS-FIXTURE.

1,389,378.

Specification of Letters Patent. Patented Aug. 30, 1921.

Application filed February 2, 1920. Serial No. 355,747.

To all whom it may concern:

Be it known that I, WILLIAM D. PATTON, a citizen of the United States, residing in Philadelphia, Pennsylvania, have invented 5 Truss-Fixtures, of which the following is a specification.

Under conditions of use hernia or rupture pads tend to turn upon the screws or other members whereby they are connected to 10 their supporting frame, and it is essential that such dislodgment should be prevented, while at the same time leaving it possible for the pad to be adjusted at will. One 15 object of my invention therefore is to provide a relatively simple, substantial and reliable device for connecting a truss pad to its supporting frame, which shall normally prevent the turning of said pad and also permit of its convenient and rapid adjustment.

A further object of the invention is to provide a novel form of pivotal connection for attaching a truss pad to its supporting frame, which may be conveniently and 25 quickly loosened to permit either the rotation of the pad so that this may be placed at any desired angle of the line of the adjacent portion of the frame, or its lateral movement to either side of its mid position.

These objects and other advantageous 30 ends I attain as hereinafter set forth, reference being had to the accompanying drawings, in which,

Figure 1 is a perspective view of a truss 35 pad and part of its associated frame, showing my invention as applied thereto;

Fig. 2 is an elevation of the rear face of the pad shown in Fig. 1;

Fig. 3 is a longitudinal vertical section on 40 the line 3—3, Fig. 2;

Fig. 4 is a fragmentary elevation of the front face of that part of the truss frame to which the pad is attached;

Figs. 5 and 6 are perspective views of the 45 opposite faces of the connecting block constituting part of my invention; and

Fig. 7 is an enlarged vertical section of a slightly modified form of my invention.

In the above drawings 1 represents a portion 50 of the body of a well-known form of truss frame, to each end of which is hinged a section 2 of relatively rigid material such as a flat bar or band of brass or other suitable material. This frame section is formed

with a longitudinally extending and relatively narrow slot 3, whose longitudinal edges are serrated as indicated at 4, for coaction with a toothed projection 5 from a circular block 6 which is perforated or centrally bored for the reception of a connecting screw 7. That face of the block opposite the toothed projection 5 is provided with a parallel sided projection 8 of such a width as to slidably fit an elongated slot formed in a metal plate 10 set 65 in the rear face of the truss pad 11. This latter is made of hard rubber or other suitable material, and is transversely recessed under the plate 10 to provide a slideway for non-rotatably holding a nut 12 threaded to 70 receive the connecting screw 7. The thickness or height of the projection 8 of the block 6 is preferably the same as or a little less than the thickness of the metal plate 10, which is fixed to the pad 11 by screws 13. 75

While the toothed projection 5 may have the form of a spur gear and the serrations 4 in the truss member 2 take the form of parallel teeth extending from face to face thereof, I preferably give said projection a 80 conical form with its teeth converging in a manner similar to those of a beveled gear, and form the serrations 4 inclined at an angle on the plane of the frame section.

With the above described arrangement 85 of parts I preferably provide also a washer 14 between the head of the screw 7 and the adjacent surface of the truss section 2, and pass said screw loosely through the passage in the block 6 which is mounted between said frame section and the plate 10 of the truss pad 11. Said screw is threaded into the nut 12 and when loosened will permit this with 90 the block 6 and its associated parts to be freely moved transversely of the truss pad while also allowing said pad to be moved longitudinally of the frame section 2 as well as rotated upon the screw 7 into any desired angular position. When properly adjusted, the setting up of the screw draws 95 the nut 12 tightly against the under side of the plate 10 and causes the teeth of the projection 5 of the block 6 to be drawn into the serrations of the teeth 4 of the slot 3.

As a consequence the truss pad is immovably held in the desired position relatively to the frame 2, for its plate 10 is rigidly and immovably clamped between the block 6 105

and the nut 12, while said block, by reason of the engagement of its projection 5 with the teeth of the frame member, is immovably held to the latter.

5 If desired the opposite sides of the slot 9 in the plate 10 may be toothed as indicated in Fig. 4, and in place of the parallel side projection 8, I may employ a second toothed projection 16 similar to the toothed projection 5, as illustrated in Fig. 7. While this construction gives a connection between the truss pad and the truss, which is more positive than that shown in Fig. 3, I have found that under practical conditions, the latter 15 form of the invention is satisfactory and meets the requirements as above described. In any case it is possible to quickly adjust the pad 11 on the frame section 2 when the screw 7 has been slightly loosened or backed 20 off, and after it has been again tightened with the truss pad in the desired position, the latter is immovably held in place without possibility of becoming loosened under conditions of use.

25 I claim:—

1. The combination of a truss frame having an elongated serrated slot, a truss pad having a toothed projection formed to non-rotatably engage the serrations of such slot

30 and means for clamping said parts together;

2. The combination of a truss frame having a serrated opening; a truss pad; a member having a toothed projection formed to coöperate with the serrations of said opening; and means for clamping the pad to the frame with the toothed projection in engagement with the serrations of said opening.

3. The combination of a frame having a 40 serrated opening; a truss pad; means for connecting said pad and frame consisting of a block mounted between them, said block non-rotatably engaging the pad and having a toothed portion entering said opening of

the frame; with means for clamping said parts together.

4. The combination of a frame having an elongated serrated opening; a block having a toothed projection extending into said opening; a truss pad formed to non-rotatably engage said block; and a screw for removably clamping the pad, block and frame together.

5. The combination of a frame having an elongated opening; a truss pad; a member 55 non-rotatably fitting said opening and also non-rotatably engaging said pad; with means for clamping the pad, frame and block together.

6. The combination of a frame having 60 an elongated opening formed with inclined teeth; a truss pad; a block detachably but non-rotatably engaging said pad and having a beveled toothed projection; and a member for immovably holding the pad, frame and 65 block together with the teeth of said latter elements in locking engagement.

7. The combination of a truss frame having an elongated serrated opening; a truss pad; and means including a toothed structure 70 coöperating with the serrations of said opening, for non-rotatably connecting said pad and the frame.

8. The combination of a truss pad; a slotted plate thereon; a nut retained in the 75 pad by said plate; a block having a portion fitting the slot of the plate and also having a toothed projection; a frame having a serrated slot for the reception of said projection; and a member engaging the nut for 80 clamping together the pad, frame and block.

9. The combination of a truss pad; a plate thereon having a serrated slot; a frame also having a serrated slot; a block having toothed portions fitting the slots of the pad 85 and frame; with means for clamping the frame, pad and block together.

WILLIAM D. PATTON.
